LUBRICATING DEVICE

Bengt E. Folke, Mamaroneck, and Ralph H. Shepard, New York, N. Y., assignors to Nathan Manufacturing Company, New York, N. Y., a corporation of New York

Application March 28, 1945, Serial No. 585,228.

8 Claims. (CL 184—27)

1

This invention relates to apparatus used for lubricating aircraft gas turbine engines.

Such apparatus must be capable of supplying oil to vital parts of the engine at varying atmospheric pressures and under extreme temperature fluctuations. The apparatus must further be adapted to be operated at high speeds common to engines of that type.

It is the principal object of this invention to provide a device to meet the aforesaid conditions which consists of a mechanical lubricator operated at high speed, a pump rotor for taking oil from a source of supply and discharging it under pressure into the lubricator, of another pump rotor for returning oil in excess of the amount that can be handled by the lubricator, as well as oil from a sump, to the source of supply, all in a simple unitary housing whereby joints and piping are eliminated and thereby the possibility of leaks.

Another object of the invention is to provide in a structure of this type automatic means for lubricating its internal working mechanism to permit operation at high speeds.

Another object is to provide in such a structure means for cooling, and carrying away the heat generated by, its internal operating parts.

Still another object is to provide in this device an automatically functioning by-pass valve for returning surplus oil fed to the lubricator into the pump rotor returning this oil to its source of supply, this valve being operable by the pressure in the oil line between the pump rotor supplying oil to the lubricator and the lubricator.

Still another object is to provide in such a structure means to prevent infiltration of air into the oil lines.

A further object is to provide a structure, embodying the aforesaid means that will be dependable in operation, can be manufactured economically and, by virtue of its construction, lends itself readily for production in quantities.

Still further objects will become apparent in the following specification in which a preferred embodiment of the invention is described and illustrated by means of the accompanying drawings in which

Fig. 1 is a plan view of a lubricating device in accordance with the principles of the invention;

Fig. 2 is a longitudinal sectional view along the plane of line 2—2 in Fig. 1;

Fig. 3 is an end view of the right hand side of the device;

Fig. 4 is an end view of the left hand side of the device with its cap removed and part of the

2

actuating member for the pistons broken away;

Fig. 5 is a longitudinal sectional view along the plane of line 5—5 in Fig. 4;

Fig. 6 is a fragmentary longitudinal sectional view of the left hand part of the device along the plane of line 6—6 in Fig. 4, the piston being shown in its suction stroke;

Fig. 7 is a fragmentary longitudinal sectional view of the right hand part of the device along the plane of line 7—7 in Fig. 3;

Fig. 8 is cross-sectional view along the plane of line 8—8 in Fig. 2;

Fig. 9 is a fragmentary sectional view along the plane of line 9—9 in Fig. 5;

Fig. 10 is a fragmentary longitudinal sectional view along the plane of line 10—10 in Fig. 1;

Fig. 11 is a cross sectional view along the plane of line 11—11 in Fig. 2;

Fig. 12 is a fragmentary cross-sectional view through one of the rotors and its surrounding parts along the plane of line 12—12 in Fig. 2;

Fig. 13 is a cross-sectional view along the plane of line 13—13 in Fig. 2, and

Fig. 14 is a fragmentary longitudinal sectional view similar to Fig. 6, but with the piston shown in its pressure stroke and illustrating a modification of the oil inlet to the lubricator housing.

Like characters of reference denote similar parts throughout the several views and the following specification.

20 is a housing having secured to it at its left hand side a block 21 through the center of which a sliding shaft 22 extends surrounded by a bushing 23. Sliding shaft 22 projects within the housing and has a thickened portion 24 within the housing provided with an oblong slot 25 and abutments 26 and 27 symmetrically disposed with respect to this slot. An end 28 of the shaft is supported within a corresponding socket in the right hand wall of the housing.

Diagonally disposed within the housing and coaxially with slot 25 is an eccentric drive 29 having its one end 30 suitably journalled within a cap 31 and its other end 32 within a corresponding socket in the wall of the housing 20 as clearly shown in Fig. 8. 33 is a worm gear forming part of this eccentric drive and 34 an eccentric adapted to contact the abutments 26 and 27 of portion 24 of the sliding shaft 22 which reciprocates the sliding shaft while the drive is being rotated.

35 is another eccentric within the slot 25 which, when the drive is rotated, will oscillate the sliding shaft while it is being reciprocated by eccentric 34.

36 is a driving shaft having its end portion 37

supported within a wall at the left hand side of the housing 20 and its other end 38 supported within the housing as will be described later on. Drive shaft 36 is equipped with a worm 39 engaging worm wheel 33 of the eccentric drive.

The extreme left hand end of sliding shaft 22 projects outwardly from the block 21 and has secured to it a slotted disc or actuating member 40. Annularly disposed in the block 21 and around sliding shaft 22 are a plurality of cylinders 41. Each of the cylinders communicates by an inlet passage 42 to an annular chamber 43 which in turn is in constant communication with an inlet 44 proper by a passage 45. Opposite the inlet passage 42 to each cylinder is a discharge passage 46 in communication with an outlet 47 from the lubricator. This is shown clearly in Fig. 5. It will be seen that the block 21 has one inlet 44 and a plurality of outlets 47, each outlet communicating with its own cylinder and each cylinder being in communication with the central chamber 43 within the block which receives its supply of oil through passage 45 from the main inlet 44.

In each of the cylinders is a slidably disposed piston 48 having its extreme left hand end project outwardly from the block 21 and having an extension 49 offset with respect to the axis of the piston and connected thereto by a bridge 50. Each of the offset extensions 49 is movably fitted within one of the slots of actuating member 40. Each extension is threaded, and each piston is fastened to the member 40 by clamping the bridge 50 against the inner face of the member 40 and by screwing a regulating nut 51 onto the threaded extension and against the outer face of the member 40 and holding it there by a lock nut 52. The innermost end of each piston 48 is provided with a V-shaped groove 53 communicating by means of a small passage 54 with its cylinder.

It will be noted that, as the sliding shaft 22 reciprocates and oscillates by reason of the eccentric drive, as previously described, each piston is also given a reciprocating and oscillating motion by virtue of the member 40 which oscillates each piston around its axis by swinging the offset extension 49 of each piston about the piston axis and reciprocates each piston by the reciprocating travel of the shaft 22. While regulating nut 51 and bridge 50 are close to the outer and inner faces of the actuating member 40, they are not clamped so tightly against its faces as to prevent oscillating motion of the piston. The pistons and cylinder, in combination, are individual force feed units actuated by the operating mechanism within the housing.

At the beginning of the stroke of each piston, i. e., when the sliding shaft is moved towards the left and the reciprocation of the piston begins, oil is drawn into each cylinder below the piston through inlet passage 42, groove 53 and passage 54. As soon as the suction stroke is completed, the actuating member is oscillated, the piston begins its pressure stroke and its groove 53 does not communicate with the inlet passage 42 but instead with the discharge passage 46. Each piston then, during its pressure stroke, discharges oil from the cylinder through passage 54, groove 53, discharge passage 46 and finally through outlet 47.

55 is a cap screwed into the left hand end of block 21 at 56 forming a chamber 57 around the actuating member 40 and the ends of pistons 48. As shown in Fig. 2 the outlet of preferably the uppermost cylinder in the block 40, instead

of being discharged through 46 and final outlet 47, has an L-shaped outlet passage 58 communicating with chamber 57. 59 are passages through the block 40 and also near its top, forming a communication between chamber 57 and the inside of housing 20.

In Fig. 14 is shown a modification of the L-shaped outlet passage 58 from the cylinder. In this figure the L-shaped passage 58 communicates with the housing 20 instead of directly with the chamber 57. In all other respects the block 21 and other parts are the same as previously described.

In an enlarged right hand end portion 60 of the housing 20 and concentric with drive shaft 36 is inserted a casing 61 which contains a rotary pump for supplying oil and other rotary pump for returning oil, each of a construction well known in the art. The pump for supplying oil 10 consists of a toothed rotor 62 directly keyed to the end 33 of the drive shaft. This rotor has cooperating with it and surrounding it a correspondingly shaped component 63 which is eccentrically mounted within the casing 61. This 15 rotor is in communication by means of ports 64 and 65 in the casing with an inlet 66 and inlet passage 66a in the wall of the housing 20, and similarly by means of ports 67 and 68 in the casing with an outlet 69 and outlet passage 69a in the wall of the housing 20, as clearly shown in 20 Fig. 13. Concentrically disposed with respect to rotor 62 with component 63, but separated therefrom by a spacer 70, is the return rotary pump consisting similarly of a toothed rotor 71 directly 25 keyed to the end 33 of the drive shaft. The teeth of this rotor cooperate with a correspondingly shaped component 72 surrounding it and which is eccentrically mounted within the casing 61. Adjacent the inner end of casing 61 is a flange 30 of a bushing 73. Bushing 73 is closely fitted into the housing 20 and together with the casing 61 itself serves as a support for the end 33 of the drive shaft 36. The return rotor communicates by means of a port 74 in bushing 73 with a correspondingly shaped port 75 in the housing, the shape of which is seen in Fig. 11, and with an inlet 76 by way of inlet passage 76a in the wall of the housing. Another port 77 through bushing 73 communicates with a correspondingly 35 shaped port 78 in the housing which in turn communicates with outlet 79 by way of an outlet passage 79a in the wall of the housing. 80 is a packing ring between the outer diameter of the casing and the housing, and 81 is a packing ring 40 between the inner diameter of the housing and the drive shaft. The outer end of casing 61 is flanged at 82 to enable it to be secured conveniently to the end of the housing 20 by means of screws 83. The end of the drive shaft 36 projects outwardly of flange 82 to be attached conveniently to a source of motive power.

84 is a drain opening in the end wall of the housing and 85 an opening through flange 82 of the casing to permit drainage issuing from opening 85 to pass through the flange into a sump conveniently located below the lubricator and which is generally also adapted to accumulate drippings, etc., from the engine.

86 is a relief valve held by a spring 87 against 45 and normally closing an opening 88 in a cage 89 secured to the housing by means of a plug 90. Opening 88 communicates by means of a bypass 91 with the outlet passage 69a of the supply rotor. Openings 92 in cage 89 are in communication with bypass ducts 93 and 94 leading into

the outlet passage 19a of the housing, valve 86 controlling communication between by-pass ducts 91 and 93 and 94. 95 is a packing ring between the housing 20 and the outer diameter of the valve cage 89.

In application to aircraft engines the oil reservoir is generally remote from the lubricator and is piped to inlet 68 of the housing. During the rotation of the drive shaft 36 oil from the reservoir is drawn into the supply rotor 62, coating with 63, through ports 65 and 64, and forced by the rotor 62 through ports 67 and 68 into housing outlet 69 which is piped to the main inlet 44 of the block supplying oil to all cylinders and pistons therein. The pistons during their reciprocation and oscillation, as previously explained, discharge oil through each one of their outlets 41 to the places which are to be lubricated. One of the piston and cylinder units, however, discharges oil, as shown in Fig. 2, into the chamber 57 filling it completely with oil and thus lubricates the actuating mechanism for the pistons with that chamber. When the chamber is full, oil will overflow through passages 59 near the top of the chamber into housing 20 which it fills up to the level of drain openings 84 and 85 to be discharged into the before mentioned sump. The lower part of the housing being filled with oil lubricates the operating mechanism within the housing so satisfactorily that the drive shaft can be run at very high speeds. A certain amount of oil is also splashed about the housing and serves to lubricate the supported ends of the drive shaft as well as the rotor pumps.

It is very important when using small metered discharges of oil for lubrication of aircraft engines that no infiltration of air takes place. This is prevented by the application of packing rings 80 and 81 in the casing, as well as 95 around the valve cage 89; all other joints are securely sealed by direct face to face contact of metal surfaces.

The second or return rotor serves the purpose of returning oil from the sump to the source of supply. If the supply rotor delivers more oil to this inlet than will be discharged by the lubricator, a pressure will begin to build up within this line and, as soon as this pressure reaches a predetermined height, the valve 86 will open and permit discharge of this surplus oil to take place through by-pass openings 88, 91, 92, 93, 94, to the outlet side of the return rotor where it combines with oil from the sump and is returned through outlet 19 in the housing to the source of oil supply.

While we have described the return of this surplus oil to the outlet of the return rotor it may, of course, also be by-passed to the inlet end of the return rotor. In such case the size of the return rotor must be slightly increased to handle the additional volume of surplus oil. Moreover, while only two rotors are shown built into the housing, it is obvious, of course, that more than two rotors could be so provided to handle oil or even other liquids for different purposes.

Many other changes in the form, proportion and combination of parts and minor details of construction may be resorted to without departing from the principles or sacrificing any of the advantages of the invention, as defined in the appended claims.

What we claim as new is:

1. In a lubricating device, a housing, a block secured to the housing having an inlet and a plurality of outlets for a lubricant, mechanical

lubricator mechanism comprising a plurality of force feed units of the piston type in said block, each unit adapted to draw in the lubricant through said inlet and discharge it from one of said outlets, operating means for said force feed units, a drive shaft for said operating means supported within the housing, at least one of said force feed units adapted to discharge a lubricant into the housing for said drive shaft and associated parts, a supply rotor and a return rotor secured to said drive shaft, said housing having an inlet and an outlet for each of said rotors, said supply rotor delivering oil to the inlet of said block, said return rotor and its inlet and outlet in the housing forming a return line, and means adapted to discharge excess oil between the supply rotor and the block inlet into said return line.

2. In a lubricating device, a housing, mechanical lubricator mechanism of the piston type secured to the housing, said mechanism having an inlet and a plurality of outlets, operating means for said mechanism including a drive shaft supported within the housing, at least one of the outlets of said mechanism being connected to the housing to discharge oil into it for the lubrication of said drive shaft and associated parts, a supply rotor and a return rotor secured to said drive shaft, said housing having an inlet and an outlet for each of said rotors, said supply rotor delivering oil to the inlet of said mechanism, said return rotor and its inlet and outlet in the housing forming a return line, and means adapted to discharge excess oil between the supply rotor and the inlet of said mechanism into said return line, said housing having an overflow opening to carry off surplus oil from within the housing while keeping said operating means submerged in oil.

3. In a lubricating device, a housing, a block secured to the housing having an oil inlet and a plurality of oil outlets, a plurality of force feed units of the piston type in said block, each unit adapted to draw in oil through said inlet and discharge it from one of said outlets, operating means for said force feed units, a drive shaft for said operating means within the housing, a casing secured to the housing forming a support for said drive shaft, a supply rotor and a return rotor within the casing and fastened to said shaft, said casing having an inlet and an outlet for each of said rotors, said supply rotor delivering oil to the inlet of said block, said return rotor and its inlet and outlet in the casing forming a return line, means adapted to discharge excess oil between the supply rotor and the block inlet into said return line, and packing means between said casing and housing to prevent air infiltration.

4. In a lubricating device, a housing, a block secured to the housing having an oil inlet and a plurality of oil outlets, a cap secured to said block forming a chamber therewith, said chamber and housing having a connecting passage through said block, a plurality of force feed units of the piston type in said block, each unit adapted to draw in oil through said inlet and discharge it from one of said outlets, actuating means for said units in said chamber and extending through the block into the housing, a drive shaft supported within the housing and operatively connected to said actuating means, at least one of said units discharging oil into said chamber and housing for the lubrication of said drive shaft and associated parts and of said actuating means, a supply rotor and a return rotor within the housing

and fastened to said shaft, said housing having an inlet and an outlet for each of said rotors, said supply rotor delivering oil to the inlet of said block, said return rotor and its inlet and outlet in the housing forming a return line, and means adapted to discharge excess oil between the supply rotor and the block inlet into said return line.

5. In a lubricating device, a housing, mechanical lubricator mechanism of the piston type secured to the housing, said mechanism having an oil inlet and a plurality of oil outlets, operating means for said mechanism including a drive shaft supported within the housing, a supply rotor and a return rotor fastened to said drive shaft within the housing, said housing having an inlet and an outlet for each of said rotors, said supply rotor delivering oil to the inlet of said mechanism, said return rotor and its inlet and outlet in the housing forming a return line, said housing having a by-pass between the outlet of said supply rotor and the return line, and a valve normally closing said by-pass adapted to be opened by excess oil pressure between said supply rotor and said lubricator mechanism.

6. In a lubricating device, a housing, a block secured to the housing having an oil inlet and a plurality of oil outlets, a plurality of force feed units of the piston type in said block, each unit adapted to draw in oil through said inlet and discharge it from one of said outlets, operating means for said force feed units, a drive shaft for said operating means supported within the housing, a supply rotor and a return rotor secured to said drive shaft within the housing, said housing having an inlet and an outlet for each of said rotors, said supply rotor delivering oil to the inlet of said block, said return rotor and its inlet and outlet in the housing forming a return line, said housing having a by-pass between the outlet of said supply rotor and the return line, and a valve normally closing said by-pass adapted to be opened by excess oil pressure between said supply rotor and said block.

7. In a lubricating device, a housing, a block secured to the housing having an oil inlet and a plurality of oil outlets, a plurality of cylinders in the block, each cylinder having an inlet passage in communication with said oil inlet and an outlet passage in communication with one of said oil outlets, an oscillating and reciprocating piston in each of the cylinders having means for alternately placing the inlet and outlets in communication with the cylinder as the piston oscillates, a sliding shaft in the block parallel to said pistons and extending into the housing, means within the housing for reciprocating and oscillating said shaft about its axis including an eccentric, a worm gear, and a drive shaft supported within the housing operatively connected to said eccentric and gear, a common actuating member fastened to said sliding shaft and connected to said pistons to force them to discharge oil from said outlets, at least one of the outlets of said block being connected to the housing to discharge oil into it for the lubrication of said drive shaft and associated parts, a supply rotor and a return rotor secured to said drive shaft within the housing, said housing

having an inlet and an outlet for each of said rotors, said supply rotor delivering oil to the inlet of said block, said return rotor and its inlet and outlet in the housing forming a return line, said housing having a by-pass between the outlet of said supply rotor and the return line, and a valve normally closing said by-pass to be opened by excess oil pressure between said supply rotor and said block.

- 10 8. In a lubricating device, a housing, a block secured to the housing having an oil inlet and a plurality of oil outlets, a plurality of cylinders in the block, each cylinder having an inlet passage in communication with said oil inlet and an outlet passage in communication with one of said oil outlets, an oscillating and reciprocating piston in each of the cylinders having means for alternately placing the inlet and outlets in communication with the cylinder as the piston oscillates, a sliding shaft in the block parallel to said pistons and extending into the housing, means within the housing for reciprocating and oscillating said shaft about its axis including an eccentric, a worm gear, and a drive shaft supported within the housing operatively connected to said eccentric and gear, a common actuating member fastened to said sliding shaft and connected to said pistons to force them to discharge oil from said outlets, at least one of the outlets of said block being connected to the housing to discharge oil into it for the lubrication of said drive shaft and associated parts, said housing having an overflow opening to carry off surplus oil from within the housing while keeping said drive shaft and associated parts submerged in oil, a supply rotor and a return rotor secured to said drive shaft within the housing, said housing having an inlet and an outlet for each of said rotors, said supply rotor delivering oil to the inlet of said block, said return rotor and its inlet and outlet in the housing forming a return line, said housing having a by-pass between the outlet of said supply rotor and the return line, and a valve normally closing said by-pass adapted to be opened by excess oil pressure between said supply rotor and said block.
